MISSOURI, ASSIGNEES TO KILLARK ELECTRIC MANUFACTURING COMPANY, OF ST.
LOUIS, MISSOURI, A CORPORATION OF MISSOURI.

INCLOSED FUSE.

1,296,808.

Specification of Letters Patent. Patented Mar. 11, 1919.

Application filed January 2, 1917. Serial No. 140,120.

To all whom it may concern:

Be it known that we, GEORGE McD. JOHNS, and JOHN B. TRESCHOTT, citizens of the United States, residing respectively at the 5 city of St. Louis, State of Missouri, and at Midland Heights, St. Louis county, Missouri, have jointly invented certain new and useful Improvements in Inclosed Fuses, of which the following is a specification, 10 reference being had to the accompanying drawing, forming a part thereof.

This invention relates generally to electric safety fuses and, more particularly, to certain new and useful improvements in 15 that class of electric safety fuses commonly known as renewable inclosed or cartridge fuses.

The chief objects of our present invention are to provide an electric safety fuse 20 in which the fusible-element or strip may be readily and conveniently renewed when blown or disrupted by an excess of current, the more expensive casing or shell and terminals or other fittings of the fuse being retained and repeatedly used; to provide a fuse 25 of the class mentioned in which, on the blowing of the original fusible element or strip, it is most difficult, if not impossible, to employ or substitute a fusible-element or strip of different or greater carrying-capacity than 30 the rated capacity of the original fuse; to provide a renewable fuse with inexpensive means adapted to indicate the blowing or disruption of the fusible-element or strip; 35 to provide an efficient fuse of the class stated of simple and economical construction, of few readily assembled and renewable parts or members, and in which the parts or members are securely held in operative relation by frictional engagement 40 therebetween; and to improve generally upon and simplify the construction of fuses of the class described.

With the above and other objects in view, 45 our present invention resides in certain novel features of form, construction, arrangement, and combination of parts, all as will hereinafter be described and afterward pointed out in the claims.

50 In the accompanying drawing—

Figure 1 is a longitudinal sectional view of an inclosed fuse of the knife-blade type embodying our invention;

Fig. 2 is an end view of the same;

Fig. 3 is a longitudinal sectional view 55 through the fuse taken approximately at right angles to the sectional view of Fig. 1.

Fig. 4 is a transverse sectional view 60 through the fuse on approximately the line 4—4, Fig. 1;

Fig. 5 is an enlarged plan view of the renewable fusible-element or strip forming 65 part of the fuse;

Figs. 6 and 7 are opposite end views of 70 the fusible-element or strip;

Fig. 8 is a side edge view of the fusible- 75 element or strip;

Fig. 9 is an elevational view, partly in longitudinal section; of an inclosed fuse of 80 the ferrule type embodying our invention;

Fig. 10 is a similar view taken approximately at right angles to the view of Fig. 9;

Fig. 11 is a plan view of one of the pairs 75 of strip-engaging and securing members or jaws of the fuse;

Figs. 12 and 13 are opposite end views of 85 the same;

Fig. 14 is a side edge view thereof; and

Fig. 15 is a transverse section through a 90 fuse of our construction, embodying a modified form of said securing-members or jaws.

Referring to the said drawing, in which like reference characters refer to like parts throughout the several views, 1 indicates the 95 fuse-casing, which is preferably an open-ended tubular shell of fibrous or other suitable insulation material, and which may be of any suitable length and diameter as required according to the desired size or current-carrying capacity of the fuse. At each 90 end, the casing or shell 1 is cut away inwardly, the casing or shell being thereby provided longitudinally with alining pairs of diametrically opposite slots 2—2; and since the construction of the fuse at each 95 end of the casing or shell 1 is substantially identical, the construction of the fuse at one end of the casing only will be here in detail described.

3 indicates a sleeve or annulus of thin 100 steel or other suitable metallic material, which is fitted about the end of shell 1 and permanently fixed to the shell in any suitable manner, as, for instance, by crimping, as at 4.

Projecting transversely or crosswise of 105 shell 1 with its ends disposed in the slots 2 and welded or otherwise fixed to the sleeve 3,

is a bar 5. This bar 5, which at its ends is approximately rectangular in shape in cross section, is intermediate its ends, for purposes shortly to appear, suitably bent longitudinally thereof into what might be described as an odd, crooked, sinuous, or peculiar shape, as, for instance, into the approximately S-shape seen particularly in Fig. 4. 7 indicates the renewable element or fusible-strip of the fuse, which may be of any suitable readily fusible metal or alloy, and which is of the desired ampere carrying-capacity, as will be well understood. This strip 7 is also of a length corresponding approximately with the length of the shell 1, the strip 7 being adapted to extend longitudinally of and within the shell, as seen particularly in Figs. 1 and 3, to one side of both the fixed bars 5. At one end of strip 7 is a preferably integral extension 8, which is bent, as at 9, over upon the strip 7 to form or provide a hook for engagement with one of the fixed bars 5 in the assembling of the fuse. At the other end of strip 7 is also a preferably integral extension 10 having a length approximately equal to or less than the internal radius of the shell 1, so that the extension 10, in the assembling of the fuse, may be conveniently and easily folded within the shell over upon, and the strip 7 thereby engaged with, the other or opposite fixed bar 5. The strip 7 is partly flat throughout its length and area; but to efficiently engage electrically with, and conform preferably to a portion of one side or face of, the bars 5, the strip 7 is pressed or otherwise formed longitudinally at its ends and approximately on opposite sides of its longitudinal axis with elongated concavities or rounded depressions 11-11 of a curvature corresponding with, and to neatly fit, a portion of the under face of the bars 5, as illustrated in Fig. 4. Similarly, extension 8, while partly flat, is suitably formed longitudinally with a convexed or rounded portion, as at 12, to conform partly to the other or upper face of one of the bars 5, the convexed portion 12 of extension 8 and depression 11 of strip 7, while partly overlapping at their inner edges, extending for the most part upon opposite sides of the longitudinal axis of the strip. Likewise, extension 10, while also partly flat, is preferably formed or provided for the same purpose in connection with the opposite bar 5 with a correspondingly convexed or rounded portion, as at 13. Thus the strip 7, when operatively positioned within the shell 1, is adapted to smoothly and neatly fit upon and engage with both sides or faces of the fixed bars 5.

14 indicates a suitable flanged or cup-shaped metallic cap, which is adapted, in the finished or assembled fuse, to snugly fit removably or detachably upon, and frictionally engage with, the sleeve 3 and provide a

closure for the end of the shell 1. The cap 14 is provided in its end wall with perforations, as at 15, constituting vents for the escape of gas from the interior evolved on the blowing of a strip 7, a screening-disk 16 disposed flatwise upon the inner face of the end wall of the cap 14 preventing the escape through the vent-perforations 15 of molten or other particles of a blown or disrupted strip. The end-cap, as well as also the screening-disk in the knife-blade type of our fuse, as illustrated in Figs. 1 and 3, are provided with an elongated approximately rectangular slot, projecting outwardly through which longitudinally of the shell 1 is a 70 knife-blade terminal 17 formed preferably by doubling or bending an elongated section of metal, preferably hard rolled copper, upon itself.

The said copper or other suitable metallic section is further bent adjacent its ends to an approximately U-shape in side elevation to provide a pair of strip-engaging members or jaws 18, the said metallic section being welded or otherwise permanently fixed to 85 the cap 14 with the strip-engaging or clamping jaws disposed inwardly of the cap, as shown. The jaws 18 are also each pressed or otherwise formed to a shape to conform to the shape of the bar 5 and the ends of the 90 strip 7, and accordingly each jaw 18 comprises a flat portion 19 and a longitudinally-disposed rounded portion 20, the rounded portions 20 of the jaws 18 being oppositely disposed and, while slightly overlapping at 100 their inner edges, lying or extending for the most part upon opposite sides of the longitudinal axis of the jaws. Thus the jaws 18, which are suitably spaced apart one from the other and which are inherently somewhat resilient or spring-like, are adapted, when the end-cap is fitted upon the shell, to 105 clampingly engage with the bar 5 and the fusible strip either hooked or folded thereupon to securely hold the same together with 110 the strip and jaws and their end-cap in approximately or substantially perfect electrical contact.

In assembling the parts of our fuse, the sleeves 3 with their bars 5 are fixed upon 115 the ends of the shell 1, as described. A fusible-strip 7 is then inserted lengthwise into the shell and at its hook 8 hooked into engagement with one of the bars 5. An end-cap 14 with its jaws 18 is then fitted 120 upon the shell and its jaws 18 forced or projected into clamping engagement with the bar 5 and said hooked end of the strip 7. The opposite end of the strip 7 is then at its extension 10 bent or folded into engagement 125 with the opposite or other bar 5, when the other end-cap 14 is similarly fitted upon the shell. On the blowing or disruption of the strip 7 on an excess of current, the end-caps 14, by a positive endwise pull thereupon, 130

may be readily removed or detached from the shell, a new strip 7 substituted, and the parts again assembled as described, the shell, end-caps, and other and more expensive parts or fittings of the fuse being retained and repeatedly used; and it will now be evident that, due to the peculiar or odd conformation or shape of the bars 5 and jaws 18, a new strip possessing the characteristics and rated capacity of the original or blown fuse-strip may only be substituted therefor. Under the frictional engagement between the caps 14 and sleeves 3, and the fuse in practice being held in suitable clips, the caps 14 are securely held from being accidentally blown off the shell on the disruption of the fusible-element or strip on an excess of current, thus in our fuse rendering the use of rivets, screws, or other holding-means for the caps unnecessary; but it will be obvious that additional means for removably or detachably holding the caps upon the shell may be provided, if desired.

The ferrule type of our fuse illustrated particularly in Figs. 9 to 14, both inclusive, is substantially similar in construction and operation to the knife-blade type of our fuse before described, and a detail description of the same here would, therefore, be more repetition and is hence omitted. In this type of our fuse, however, in which the end-caps or ferrules form the terminals of the fuse, a suitable section of copper or other conducting material is merely bent to an approximately U-shape in side elevation to provide the strip-engaging or clamping jaws 18', which are welded or otherwise fixed at their bight, as at 21, to the inner face of the end wall of the cap 14', slots in the end-caps 14' to accomodate knife-blade terminals being omitted.

And preferably both types of our fuse are equipped or provided with comparatively inexpensive means for indicating visually the disruption of the fusible strip. For this purpose, the wall of shell 1 is provided approximately centrally with a relatively small transverse aperture 22, in which is seated a flanged cup 23, in which cup is contained a suitable chemical or chemical-mixture adapted to change color under the influence of heat. Or this chemical or chemical-mixture, we preferably employ a mixture 24 including iodid of copper and iodide of mercury in approximately equal parts, together with gum arabic of other suitable binder. This mixture normally is of a red color, but under the influence of heat evolved on the blowing of a fusible-strip 7 and at approximately 140° F., turns black in color, the mixture on cooling again assuming its normal red color. Thus the blowing or disruption of a fusible-strip 7 is substantially at once visually indicated.

65 Disposed in the cup 23 over the mixture 24

is a retaining section or window 25 of celluloid, mica, or other suitable transparent material.

In the knife-blade type of our fuse, we may further, in practice, detachably place 70 over the end-caps 14 suitable cup-shaped members 26 of thin fiber or other insulation material to prevent, for instance, any shock or the like to a user in removing a fuse from an uninterrupted or closed circuit. 75

From the foregoing, it will be evident that our fuse is comparatively simple in construction, may be economically and cheaply manufactured, and comprises readily assembled and renewable parts. And it is to be 80 understood that the fusible-strip 7 at its ends, as well as the jaws 18 or 18', may have, if desired, the modified or substantially full S-shape form in cross section, as illustrated in Fig. 15, to correspond or conform fully 85 to the shape of the bars 5, and that other changes in the form, construction, arrangement, and combination of the several parts of our fuse may be made and substituted for those herein shown and described without 90 departing from the nature and principle of our invention.

Having thus described our invention, what we claim and desire to secure by Letters Patent is:

1. A renewable fuse of the class described comprising, in combination, a shell, a bar extending transversely across the shell at an end, the bar being fixed at its ends to the shell, a fuse-strip extending longitudinally 100 within the shell, the strip having an end removably disposed upon said bar, an end-cap fitting removably upon the shell, and coöperating jaws on the end-cap projecting into the shell, said jaws clampingly engaging 105 removably with the strip and bar for detachably securing the same together.

2. A renewable fuse of the class described comprising, in combination, a shell, a bar extending transversely across the shell at an 110 end, the bar being fixed at its ends to the shell, a fuse-strip extending longitudinally within the shell, the strip having an end bent to lie upon opposite sides of and infold the bar, an end-cap fitting removably upon the shell, and a pair of coöperating jaws on the cap projecting into the shell, said jaws clampingly engaging the bent end of the strip and the infolded bar 115 for detachably securing the strip and bar 120 together.

3. A renewable fuse of the class described comprising, in combination, a shell having diametrically opposite slots at its end, a sleeve fixed upon the said end of the shell 125 and concealing said slots, a bar extending transversely across the shell at its said end, the bar having its ends projecting through said slots and fixed to the sleeve, a fuse-strip extending longitudinally within the 130

- shell, the strip having an end bent to lie upon opposite sides of and infold said bar, an end-cap fitting removably upon the sleeve, and a pair of coöperating jaws on the cap projecting into the shell, said jaws clampingly engaging the bent end of the strip and the infolded bar for detachably securing the strip and bar together.
4. In a renewable fuse, the combination 10 with a shell, of a bar extending transversely across, and having its ends fixed to, the shell, said bar intermediate its ends being sinuous in shape in longitudinal section, and a fuse-strip adapted for insertion within the shell 15 and to engage at an end with said bar, the strip having a shape at its said end to conform approximately to the shape of the bar.
5. In a renewable fuse, the combination 20 with a shell, of a bar extending transversely across, and having its ends fixed to, the shell, the bar intermediate its ends being sinuous in shape in longitudinal section, and a fuse-strip adapted for insertion within the shell 25 and at an end to extend upon opposite sides of and infold said bar, the strip having a shape at its said end to conform approximately with the opposite side faces of the bar.
6. In a renewable fuse, the combination 30 with a shell, of a bar extending transversely across, and having its ends fixed to, the shell, the bar intermediate its ends being sinuous in shape in longitudinal section, a fuse-strip adapted for insertion within the shell and at 35 an end to extend upon opposite sides of and infold said bar, the strip having a shape at its said end to conform approximately with the opposite side faces of the bar, an end-cap adapted to fit removably upon the shell, and a pair of coöperating jaws on the end-cap adapted to clampingly engage said end of the strip and the infolded bar to secure the strip and bar detachably together, said jaws having a shape in cross section to 45 conform approximately with the opposite side faces of the bar.
7. In a renewable fuse, an open-end shell, a sleeve fixed on an end of the shell, a fuse-strip supporting-bar extending transversely 50 across the shell and fixed at its ends to said sleeve, said bar being sinusoidal in shape in longitudinal section, a fuse-strip disposed longitudinally within the shell and supported at an end on said bar, said strip having 55 a shape in cross section at its end conforming approximately to the shape of said bar, a cap removably fitting upon the sleeve and providing a closure for the end of the shell, and a pair of cooperating jaws on the cap re- 60 movably engaging with the strip and bar for detachably securing the same electrically together, said jaws having also a shape in cross section conforming approximately to the shape of said bar.
8. In a fuse, a flat fuse-strip provided 65 within its area with a longitudinally disposed depression.
9. In a fuse, a flat fuse-strip provided at each of its ends and within its area with a longitudinally disposed rounded depression, 70 said depressions lying for the most part upon opposite sides of the longitudinal axis of the strip.
10. In a fuse, a fuse-strip adapted at its end to engage the opposite faces of a sinuous supporting-bar, the strip comprising an end-portion sinuous in shape to conform approximately with one face of the bar, and a foldable extension sinuous in shape to conform approximately with the opposite face 75 of the bar.
11. In a fuse, a fuse strip provided longitudinally with elongated rounded depressions, and extensions on the fuse strip provided also with rounded depressions, the depressions of said extensions opposing the depressions of the strip. 85
12. In a fuse of the class described, a shell, a fuse-strip within the shell, an end-cap fitting upon the shell and having engagement with the strip, and an insulation-cap fitting upon the shell over said end-cap. 90
13. In a fuse of the class described, the combination with a shell, of bars extending transversely across the shell at its end, said 95 bars having their ends fixed to the shell, a fuse-strip fitting within the shell and engaging at its ends with the corresponding faces of both said bars, said strip having extensions at its ends infolding, and engaging the opposite faces of, said bars, and end-caps fitting upon the shell and having electrical connection with the strip. 100
14. In a fuse of the class described, the combination with a shell, sleeves fixed upon the shell at its ends, bars extending transversely across the shell at its ends, said bars having their ends projecting through the shell and fixed to said sleeves, a fuse-strip fitting within the shell and engaging at its 110 ends with the corresponding faces of both said bars, foldable extensions on said strip infolding, and engaging the opposite faces of, said bars, and caps fitting upon the sleeves and providing closures for the ends 115 of the shell, the caps having electrical connection with the strip.
- In testimony whereof, we have signed our names to this specification.
- GEORGE McD. JOHNS.
JOHN B. TRESCOTT.
